UNITED STATES PATENT OFFICE

EDWIN K. HAAS AND ROBERT S. DURLING, OF BALTIMORE, MARYLAND

APPARATUS FOR BREAKING IN TOBACCO PIPES

Application filed April 2, 1931. Serial No. 527,230.

This invention relates to apparatus for breaking in tobacco pipes. The object of the invention is to provide an automatic device which is simple and easy of operation and which will effectively break in a pipe so as to give it substantially the same treatment as it would receive through relatively long use by a smoker.

Referring to the accompanying drawing, 10 which is made a part hereof and on which similar reference characters indicate similar parts,

Figure 1 is a view in elevation of the apparatus,

15 Figure 2, a vertical section of the same, and Figure 3, a detail of a modified form.

In the drawing numeral 10 indicates a tank which is made air-tight and which has in its upper end a tube 11 to which a preferably 20 flexible connection 12 may be attached, the other end of the connection being slipped over the end of a pipe 13 which is to be treated. The pipe may be supported in a suitable bracket 14 secured upon the top of the tank.

25 In the lower part of the tank is positioned a tube 15 to which may be attached a water conduit 16 here shown as a flexible hose. Within the tank and bent in the form of an inverted U is a tube 17 to the outer end 18 of 30 which may be attached a flexible or other tube 19 for carrying off water from the tank.

In operation the tube 16 is preferably attached to a water spigot or other source of water. As the tank 10 is filled the air in the 35 top of the tank passes out through the pipe stem into the atmosphere, this continues until the tank is filled to the neck of the tube as indicated at line 20. When the water reaches this level it flows out through the tube, the 40 tube acting as a siphon until the tank is emptied to the level indicated by the line 21. As the water flows out of the tank it creates a vacuum in the top of the tank which causes a suction through the pipe stem in the manner produced by a smoker. The smoke is 45 therefore drawn into the tank so long as the water is flowing out of the tank. As soon as the water reaches the level 21, the siphon is broken and the tank begins to fill again. 50 Filling of the tank forces the air and smoke

back out through the tube 12 and the stem of the pipe. The operation continues alternately drawing in and forcing out the smoke through the pipe. This operation may be kept up until the pipe has been broken in. When once started the apparatus will work automatically without any attention on the part of the operator other than supplying the pipe with new tobacco when a pipe-full 55 has been consumed.

One feature of importance is that the tube 11 is preferably U-shaped and its lower end extends well down into the tank. The air and smoke drawn through the pipe therefore are cooled by the water about the tube. The 60 air and smoke cool the pipe as they are expelled.

In the modified form shown in Figure 3 the tube 11' terminates above the level of the liquid in the tank 10' but does not extend 65 down through the water in the tank. This makes a somewhat simpler form of apparatus.

It will be obvious to those skilled in the art that various changes may be made in our device without departing from the spirit of the invention and therefore we do not limit ourselves to what is shown in the drawing and described in the specification, but only as indicated by the appended claims.

Having thus fully described our said invention, what we claim as new and desire to secure by Letters Patent, is:—

1. An apparatus for breaking in tobacco pipes comprising a tank having an inlet for liquid and a siphon outlet for the same, a smoke inlet tube adapted to be attached to a pipe to be broken in, said tube extending into and well down in the tank and having its inner end positioned above the highest water 75 level in the tank, substantially as set forth.

2. An apparatus of the kind described comprising a tank having a bracket thereon adapted to receive the stem of a pipe, a water inlet adjacent the bottom of the tank 85 and a water outlet from the tank in the form of a U-tube which serves as a siphon from said tank, the water flowing in through said inlet and out through said outlet tubes serving to create alternately a pressure and a 90

partial vacuum in the top of the tank and a flexible tube connected at one end to the mouthpiece of the pipe, the other end of the tube communicating with the space in the tank above the highest portion of the siphon, substantially as set forth.

3. An apparatus of the kind described comprising a sealed tank having an inlet and an outlet for water, the outlet being in the

10 form of a tube having an open end and a bent portion extending upwardly in the tank to provide a siphon for emptying the tank, and a second tube extending into said tank having its inner end communicating with the space above the water level in the tank, substantially as set forth.

15 4. A device for the purpose described comprising a closed tank, an inlet for delivering liquid into the tank and a siphon for drawing it out of the tank, the siphon being so arranged as to empty the tank faster than the inlet fills it to effect alternate filling and emptying of the tank, and a smoke tube extending into said tank, the inner end of said tube being above the high water level in the tank, substantially as set forth.

20 5. A device for the purpose described comprising a closed tank, an inlet for delivering liquid into the tank and a siphon for drawing

25 it out of the tank, the siphon being so arranged as to empty the tank faster than the inlet fills it to effect alternate filling and emptying of the tank, and a smoke tube extending into said tank, the inner end of said

30 tube being above the high water level in the tank, said air inlet comprising a U-tube which has its open end above the water level in the tank and its bent portion extending down into the water in the tank whereby smoke is cooled as it passes through said tube to and from the air space above the water in the tank on the rise and fall of the water in the tank, substantially as set forth.

35 6. A device for the purpose described comprising a closed tank, an inlet for delivering liquid into the tank and a siphon for drawing it out of the tank, the siphon being so arranged as to empty the tank faster than the inlet fills it to effect alternate filling and

40 emptying of the tank, and a smoke tube extending into said tank, the inner end of said tube being above the high water level in the tank, said smoke tube comprising a short tube secured in the tank and having its inlet 45 end communicating with the space above the water in the tank, substantially as set forth.

50 65 In witness whereof, we have hereunto set our hands at Baltimore, Maryland, this 30th day of Mch., A. D. nineteen hundred and thirty-one.

EDWIN K. HAAS.
ROBERT S. DURLING.
